DESIGN FOR AN AUTOMOTIVE SPRING SHACKLE SIDE LINK

Charles H. Sayre, Elmira, N. Y., assignor to
Trayer Products, Incorporated, Elmira, N. Y.,
a corporation of New York

Application March 22, 1939, Serial No. 83,753

Term of patent 14 years

To all whom it may concern:

Be it known that I, Charles H. Sayre, a citizen of the United States, residing in Elmira, county of Chemung, and State of New York, have invented a new, original, and ornamental Design for an Automotive Spring Shackle Side Link, of which the following is a specification, reference being had to the accompanying drawing, forming a part thereof.

In the drawing,

Fig. 1 is a perspective view of an automotive spring shackle side link, showing my new design; and

Figs. 2, 3 and 4 are respectively front elevational, side elevational and rear elevational views thereof.

I claim:

The ornamental design for an automotive spring shackle side link, substantially as shown.

CHARLES H. SAYRE.
